CLAIM

The ornamental design for a chair, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front perspective view of a chair according to my new design; and,

FIG. 2 is a rear perspective view of the chair of FIG. 1. The dash-dash broken lines in the figures and the areas with translucent shading within the dash-dash broken lines show portions of the chair that form no part of the claimed design.
